SELECTIVE ADSORPTION OF LUBRICANTS

Henry W. F. Lorenz, Jersey City, N. J.

Application July 18, 1945, Serial No. 605,658

15 Claims. (Cl. 196—1)

1

This invention relates to the selective adsorption of lubricants. More particularly the invention relates to the selective adsorption of an oiliness agent out of lubricating oils and the products obtained thereby.

When a good grade of lubricating oil is placed between two steel surfaces which are to be lubricated a surface active substance hereinafter termed "oiliness agent" spreads as a film over the surface of the metal and is adsorbed in the pores of the metal as well as coating the surface. Depending upon the amount of oiliness agent in the oil and nature of the oil, the film will have different thicknesses with the result that the thicker the film the lower will be the surface friction within the bearing. The more polar the oil the better the oiliness film, the more complex the molecular structure, the greater the ionic charge of the molecule and the greater the polarity. Different metals have different abilities to adsorb or build up a thicker film or greater amount of oiliness agent on the surface and accordingly bearings made up of different types of metal alloys are in use in an effort to provide a good oiliness film and cut down the surface friction.

Lubricants made from Pennsylvania crude which are made up largely of saturated hydrocarbons, contain a comparatively large amount of the complex molecular structure hydrocarbon oiliness agent which is quite resistant to decomposition by heat from friction in the bearings. For this reason Pennsylvania grade lubricants have been favored principally upon their ability to maintain the original composition of the oiliness agent and hold a good lubricating film.

I have found that powdered and finely grained metals have a more selective adsorption property for oiliness agents. Furthermore, some of the lower melting metals have a greater capacity for adsorbing oiliness agents than some of the higher melting metals. Some metals which have proven to be very desirable as bearing metals depend upon their ability to build up a good film of oiliness agent over their surfaces to give antifriction lubrication and this property of maintaining the oiliness film is responsible for their use as bearings rather than the friction bearing quality of the metals.

I have also discovered that when an alloy made up of good oiliness agent adsorbing metals has adsorbed an oiliness agent on the surface, this oiliness agent may in turn be separated from the alloy by melting the alloy. The melting of the alloy contracts the metal and expels the oil-

2

iness agent that has been adsorbed in the pores and on the surface of the metal. The oiliness agent thus released may be separated from the molten metal by decantation, filtering or centrifuging.

The complex molecular structure of oiliness agents prevents them from being separated from lubricating oils by distillation, because they are easily decomposed at high temperatures. By adsorbing the oiliness agents on solid alloys which melt at comparatively low temperatures or below the decomposition temperatures of the oiliness agent, the oiliness agent may be separated selectively from the oil in its naturally occurring state.

The primary object of the present invention is to provide a method of selectively separating oiliness agent from lubricating oils.

Another object of the invention is to provide a method of separating oiliness agent from lubricating oils at temperatures at which the agent will not be decomposed or destroyed.

A further object of the invention is to provide a method of separating oiliness agent from lubricants in increments while preserving its advantageous and film-forming properties.

With these and other objects in view, the invention consists in the method of extracting oiliness agents from lubricants hereinafter described and particularly defined in the appended claims.

The various features of the invention are illustrated in the accompanying drawing, which is a diagrammatic flow sheet of an apparatus in which the preferred method of extracting oiliness agent may be carried out.

The oiliness agent may be extracted from a lubricating oil in a batch process or in a continuous process. In the drawing is illustrated an apparatus in which the oiliness agent may be extracted continuously. The lubricating oil is drawn from a container 10 and flows into a mixer 12 through a line 14. Simultaneously a low melting alloy which preferably is in a molten or granular state is drawn from a hopper 16 and flows through a control valve 18 into the mixer 12. The mixer is provided with a heating jacket 20 to provide a heating space 22 through which a heating medium, such as Dowtherm, may be circulated to provide sufficient temperature in the mixer 12 for melting the alloy while in contact with the oil. The mixer preferably is provided with a series of stirring blades 24 which are rotated by means of a pulley 25 and driving means not shown. The speed of rotation of the mixer

24 is such that when the alloy becomes melted it will be broken up into very fine particles while in contact with the oil. The mixture of finely pulverized metal and oil then flows by gravity through a valved line 26 into a mixing cooler 28. In the cooler 28 the mixture of oil and molten metal is cooled while being stirred in order to break up the metal into a solid, finely granular or pulverized material, in contact with the oil. By breaking up the metal into the fine particles the surface structure is porous and greatly expanded. This porous surface provides a means by which a large amount of oiliness agent may be drawn into the pores and coated over the surface of the metal particles.

Depending upon the type of alloy metal a greater or a smaller amount of oiliness agent may be adsorbed from the oil. Metals which are desirable for the purpose of making alloys which are low-melting and which have a large adsorption capacity are copper, zinc, lead, tin, antimony, silver and aluminum. Alloys containing these metals can be made up which will have a melting point below 200° C. and which have a high adsorbing capacity for oiliness agent. Copper, cadmium and silver have particularly high adsorptive properties when they are alloyed with other low melting metals. I do not of course, confine myself to alloys of the above-mentioned metals. Others can be employed, of which the following is only a partial list:

Per Cent	Per Cent	Per Cent	Per Cent	Melting Point, °C.
Bismuth 52	Lead 40	Cadmium 8		91.5
Bismuth 50-70	Lead 25	Cadmium 10-10		75.5
Bismuth 53	Lead 40	Cadmium 32		.96
Bismuth 53		Cadmium 21		103
Bismuth 52	Lead 32			96
Bismuth 50	Lead 27	Cadmium 10		65
Bismuth 50	Lead 27.1			.65
Bismuth 40	Lead 40			111
Bismuth solder				110
Bismuth 56	Lead 32	Cadmium 18		145
Bismuth 58	Lead 44			125
Bismuth 35-50	Lead 32	Cadmium 18		137
Bismuth 35-50	Lead 24-35	Cadmium 10		145
Bismuth 50	Lead 25	Cadmium 12.50		70
Bismuth		Cadmium		65.5
Bismuth		Cadmium		91.5
Bismuth	Lead			137
Antimony 12.50		Copper 12.50		149
	Lead	Cadmium solder and several per cent of Antimony or Mercury.		181
				198
				233

Mercury amalgams.—With lead, or tin, or zinc, or cadmium, or bismuth, or silver, etc.:

Lead, antimony Melting point 230° C. 55
Lithium metal Melting point 186° C.
Sodium metal Melting point 97° C.
And their alloys, etc.

Some oiliness agents may be decomposed at temperatures slightly lower than 200° C. but it 60 has been found to be desirable to choose those lubricants which will provide an oiliness agent that is fully stable at temperatures up to 200° C. in order to provide an oiliness agent which can be effectively blended with other lubricants in building up a high grade lubricant.

It has been found that from high molecular weight Pennsylvania grade lubricating oils and from saturated, synthetic lubricating oils made by the hydrogenation of carbon monoxide from 0.3% to 0.5% by weight of the lubricant can be adsorbed by the metal in a single treatment with the metal. A single treatment of the oil with the metal, however, does not adsorb all of the oiliness agent in the oil and therefore it is prefer-

able to remove the oiliness agent in increments by repeated treatments of the oil with the powdered metal.

After the oiliness agent has been adsorbed in the pores and on the surface of the fine grained metal in the cooling mixer 28, this metal is then separated from the oil by means of centrifugal force. To accomplish this the mixture of metal and oil passes through a valved line 30 into a centrifuge 32 where the oil passes through a porous screen and is collected in a receiver 34. From the receiver the oil is preferably returned by means of a pump through a line 36 back to the storage tank 10. If desired, fresh oil may be continuously introduced into the storage tank 10 and oil partially exhausted of its adsorbent agent may be drawn off through a line 38. The powdered metal with the oiliness agent adsorbed thereon is removed from the centrifugal bowl by means of a scoop 40 and passed through a line 42 or other conveying means to a mixing heater 44. The mixing heater 44 has substantially the same construction as the heater 12, having a heating jacket 46 which may be heated by Dowtherm for the purpose of melting the alloy. Preferably the powdered alloy with oiliness agent therein is stirred by means of a stirrer 48 while being heated to assist in effecting a heat transfer to quickly melt the alloy. When the alloy melts the physical structure of the metal shrinks to expel the oil from its surface and pores and the

65 The Dowtherm for heating the metal in the heaters 12 and 44 is preferably circulated through a tubular heater 62 by means of a hot oil pump and circulates through the lines 64 and 66 to the jackets 20 and 46. Cooled Dowtherm is returned to the heating coil through line 68 and 70.

70 It will be understood that it is not essential to return the alloy from the centrifuge 52 in a molten state back to the heater 12, but preferably this is carried out to facilitate ease in han-

dling the metal and to conserve heat. The metal may be cooled and returned to the hopper 16.

Tests which have been run indicate that up to 1.5 to 2.0% by weight and more of the oil may be removed from a lubricant as an oiliness agent by the above described process. It is found, however, that if a batch of oil is treated by continuously subjecting the oil to different bodies of powdered or finely granulated alloy much more oiliness agent is recovered in the first treatment than in the succeeding treatments. It is found desirable, therefore, that the oil should be recirculated into contact with the powdered alloy at least five to six times to recover the maximum amount of an oiliness agent.

Depending upon the type of metal used as an adsorbing agent and the type of lubricant, it has been found that the ratio of alloy to oil may vary from one to two parts by weight of alloy to five to ten parts by weight of oil.

It has also been found that when efficient stirring apparatus is employed the alloy may be effectively melted and broken up into finely divided particles when the temperature of the alloy is not more than five to ten degrees above its melting point.

The oiliness agent which has been extracted from lubricating oil may be used as an additive or blending agent with other lubricants to build up an effective film to reinforce lubricants being used. The oiliness agent may be added to lubricants that have been partially exhausted by use or it may be added to new lubricants in order to build up their oiliness properties. It has been found that the addition of 0.5 to 2.0% by weight of the oiliness agent will provide a good and effective lubricant for most purposes. Furthermore oiliness agent may be extracted from lubricants that have the ability to stand a high temperature of friction heat without decomposition and such oiliness agent added to lubricants that ordinarily will not stand such temperatures will improve the lubricants in this respect. This oiliness agent may be used, therefore, in blending with oils which have poor oiliness characteristics but excellent viscosity characteristics, and thus build up new and effective lubricants.

Although the oiliness agent has been described as being extracted from oily paraffinic lubricants and particularly high molecular weight hydrocarbons, the invention is not limited to this purpose but may be utilized for extracting the oiliness agent from almost any type of satisfactory lubricating oil.

It is to be understood that the oiliness agent which originally exists in the lubricating oil will, when extracted from the lubricating oil by the process of the present invention contain some of the lubricating oil. It is preferred to have some of the original lubricating oil associated with the oiliness agent to assist in separating the oiliness agent from the metallic adsorptive medium and to assist in blending the agent with other lubricating oil.

The preferred form of the invention having been thus described, what is claimed as new is:

1. A method of extracting oiliness agent from a lubricating oil containing an oiliness agent comprising: thoroughly wetting a solid metal having a melting point below 200° C. with a lubricating oil to impregnate and coat the surface of the metal with oil, separating unattached oil from the metal, melting the metal to set free the attached oiliness agent and recovering the oiliness agent by gravity separation.

2. The method defined in claim 1 in which the metal is a low melting alloy.

3. The method defined in claim 1 in which the lubricating oil is a high boiling, high molecular weight paraffine oil.

4. The method defined in claim 1 wherein the lubricant is subjected to repeated treatments of the metal to extract oiliness agent in increments.

5. The method defined in claim 1 in which the metal is reduced to a finely granular solid form to condition it for contact with the oil to attach the oiliness agent thereto.

10 6. The method defined in claim 1 in which the metal is mixed with oil, the mixture heated to melt the metal, and the heated mixture vigorously agitated to break up the metal into finely dispersed form while in contact with the oil, the metal then being solidified in contact with the oil while being agitated to increase the amount of oiliness agent attached to the metal.

15 7. The method defined in claim 1 in which the molten metal is separated from the oiliness agent and mixed while in a molten state with more oil, then agitated and cooled to reduce the metal to a solid, finely granular state for attaching oiliness agent thereto.

20 8. The method defined in claim 1 which is carried out as a continuous cyclic method in which oil is repeatedly re-treated by the metal.

30 9. The method defined in claim 1 in which a low melting alloy is mixed with the oil, the mixture heated to melt the alloy and the heated mixture vigorously agitated to break up the alloy into a finely dispersed form while in contact with the oil and solidifying the alloy in fine granular form in contact with the oil to increase the amount of oiliness agent attached to the alloy.

35 10. The method defined in claim 1 which is carried out as a continuous cyclic method in which the metal and oil are repeatedly re-treated until 1.5 to 2.0% by weight of the oil has been removed as oiliness agent.

40 11. The method defined in claim 1 in which the weight of metal to the weight of oil is in the ratio of one part by weight of metal to two to ten parts by weight of oil.

45 12. The method defined in claim 1 in which the gravity separation is a centrifugal force separation.

50 13. A method of extracting an oiliness agent from a hydrocarbon oil containing the same comprising: thoroughly wetting a finely divided solid metal substance having a melting point below the temperature of the beginning of decomposition of said hydrocarbon oil to impregnate and coat the surface of said finely divided solid metal with oiliness agent in the oil; separating the unattached oil from the solid metal particles; melting and agglomerating the metal particles to a liquid metal mass; recovering oiliness agent from said agglomerated solid metal mass by gravity separation; and cooling the metal to solidify the same ready for further use in the method.

55 14. A method of extracting oiliness agent from a hydrocarbon oil containing the same as set forth in claim 13 comprising: placing metal having a melting point below the temperature of the beginning of decomposition of said hydrocarbon oil and the hydrocarbon oil to be treated in an enclosed container and heating to a temperature sufficient to melt the metal; vigorously agitating the metal and oil during heating to break up the molten metal into finely divided liquid particles in contact with the oil to increase the surface 60 75 of metal exposed to the oil; cooling the oil and

liquid metal while simultaneously stirring to solidify the metal and to adsorb the oiliness agent on the surface of the metal particles; arresting the stirring; separating unattached oil from the solid metal particles; melting the metal particles to agglomerate them into a single mass to set free adsorbed oiliness agent; and recovering the oiliness agent separated from the metal by gravity separation.

15. A complex high molecular weight hydrocarbon oiliness agent extracted from a high molecular weight hydrocarbon lubricating oil by adsorption on a low melting, porous metal surface while cold and released from the metal surface by melting the metal, said agent being capable of producing a thicker oil film on a surface to be lubricated than the lubricating oil from which it is extracted will form, and said oiliness agent

having a greater ionic charge on its molecule than the ionic charge of the molecule of the lubricating oil from which the agent is extracted.
